A black and white line drawing of a building. The building has a gabled roof with a chimney on the left. A sign is mounted above the entrance, which is flanked by two columns. The sign contains the text 'Invento' at the top, 'A. M. Drake' in a large serif font in the middle, 'attorneys' in a smaller font below it, and 'Soliciting & Notary Public' at the bottom. The drawing is done in a simple, sketchy style.

UNITED STATES PATENT OFFICE.

ALDEN M. DRAKE, OF WORCESTER, MASSACHUSETTS, ASSIGNOR TO HEALD MACHINE COMPANY, OF WORCESTER, MASSACHUSETTS, A CORPORATION OF MASSACHUSETTS.

FEED MECHANISM FOR GRINDING-MACHINES.

1,281,720.

Specification of Letters Patent.

Patented July 3, 1917.

Application filed September 26, 1916. Serial No. 122,305.

To all whom it may concern:

Be it known that I, ALDEN M. DRAKE, a citizen of the United States, residing at Worcester, in the county of Worcester and 5 State of Massachusetts, have invented a new and useful Feed Mechanism for Grinding-Machines, of which the following is a specification.

This invention relates to a feed mechanism for grinding machines of the type in 10 which the work is supported upon a rotary table, and the grinding wheel is mounted on a slide and is movable toward and away from the axis of the table.

15 It is the object of my invention to provide improved feed mechanism for grinding machines of this type, suitable provision being made for changing, stopping and reversing the feed of the wheel slide, and also for 20 changing and stopping the table drive.

With this object in view one feature of 25 my invention relates to the provision of a drive shaft having a set of change gears fast thereon and meshing with each of two sets of change gears loose upon their respective 30 shafts. Any one of these loose gears may be connected with its shaft by means of manually slidable keys. I also provide suitable driving connections between one of said 35 shafts and the wheel slide, which connections include, in the preferred form, a vertical shaft and provision for rendering the same operative, including a worm and worm wheel and a friction clutch. Connections are also 40 provided between the third shaft and the rotary table through which the latter is driven.

Further features of my invention will be 45 hereinafter described and more particularly 50 pointed out in the appended claims.

A preferred form of my invention is 55 shown in the drawings in which—

Figure 1 is a partial side elevation of a 60 grinding machine with my improved feed mechanism embodied therein;

Fig. 2 is an enlarged sectional detail of 65 certain of the parts shown in Fig. 1;

Fig. 3 is a vertical sectional view taken 70 along the line 3—3 in Fig. 1, and;

Fig. 4 is a detail view of the mechanism 75 for shifting the clutch which controls the feed of the wheel slide.

Referring to the drawings, the wheel W is 80 mounted on a shaft 10 rotatable in bearings in a slide 11 and provided with a wide- 85

faced pulley or drum 12 through which it is 90 rotated by a belt not shown. The slide 11 is longitudinally movable in guide-ways on the frame 14, and is provided with a rack 15 (Fig. 3) through which it is moved longitudinally by a feed mechanism to be described.

In the form of machine shown in the drawings the work is supported upon a magnetic chuck 16 (Fig. 1) mounted upon a 10 vertical shaft 17 rotatable in a conical bearing 18. The shaft 17 is herein shown as provided with a gear wheel 19 driven by a pinion 20 mounted on a shaft 21 which is driven through bevel gears 22 and 23. Any other 15 suitable connections between the shaft 17 and the gear 23 may be substituted as desired. The mechanism for driving the bevel gear 23 will be hereinafter described.

The gear box 30 of the grinding machine 20 contains a drive shaft 31 rotatable in bearings 32, and having a set of change gears 33 fixed thereon. A gear 34 is loosely mounted on the shaft 31 and forms one member of a friction clutch which may be tightened by 25 movement of the sleeve 35 to the right, the gear 34 being thereafter effective to drive the shaft 31.

The sleeve 35 is controlled by a yoke 36 30 pivoted to the gear box at 37 and connected by a link 38 to a lever 39 having a handle 40 by which the clutch may be manually operated. The gear 34 is in mesh with a pinion 41 fast on a short shaft 42 rotatable 35 in a bearing 43 and having a pulley 44 secured thereto. The pulley 44 is belt-connected to the main driving shaft of the grinding machine, and through these connections the shaft 31 may be continuously 40 rotated.

A shaft 50 is mounted in bearings 51 parallel to the shaft 31 and a set of change gears 52 is loosely supported on the shaft 50. The gears 52 mesh with the gears 33 tight on the shaft 31, and are rotated whenever the clutch 35 is tightened. Any suitable provision may be made for connecting a selected gear 52 with the shaft 50. In Fig. 2 I have shown a sliding key 53 pivoted at 54 to a rod 55 slidable longitudinally in the shaft 50, and provided with a series of grooves 56 which give the rod the form, in effect, of a circular rack. This rack is engaged by a pinion 57 connected to a hand wheel 58 (Fig. 1), and through these connections the 50

key 53 may be manually moved to different longitudinal positions. A spring 59 (Fig. 2) holds the key 53 in engagement with the selected gear 52. By proper selection of 5 gears, the shaft 50 is driven in the desired speed ratio from the shaft 31.

A clutch collar 60 is slidably mounted upon the shaft 50 and is provided with teeth at its opposite ends adapted to engage 10 corresponding teeth on the ends of bevel pinions 61 and 62 loosely mounted upon the shaft 50. These pinions are in mesh with a bevel gear 63 secured to a shaft 64 (Fig. 3) rotatable in bearings 65 in the gear box, 15 and having a worm 66 mounted thereon, as shown by dotted lines in Fig. 3. The worm 66 drives a worm wheel 67 loosely mounted on a vertical shaft 68 rotatable in bearings 69 and having a pinion 70 at its upper end 20 meshing with the rack 15 on the wheel slide 11.

The worm wheel 67 is secured by pins 71 to a clutch member 72 also loose upon the shaft 68. An inner clutch member 73 is 25 keyed to the shaft 68 and may be caused to frictionally engage the member 72 by means of a sliding sleeve 74 controlled through a yoke 75 (Fig. 4). The yoke 75 is secured to a shaft 76 to which is also secured an arm 30 77 connected by a link 78 to a lever 79 having a handle 80. The feed of the wheel slide may thus be started and stopped by manual movement of the lever 79.

A bevel gear 81 is keyed to the vertical 35 shaft 68 and meshes with a bevel gear 82 fixed to a horizontal shaft 83 on which a hand wheel 84 is rotatably mounted. A clutch collar 85 constitutes means for connecting the hand wheel to the shaft 83 and 40 when thus connected the wheel slide may be moved manually in either direction. As the shaft 83 is rotated whenever the wheel slide is moved by power or otherwise, it is usual to release the hand wheel 84 by withdrawing 45 it from the collar 85 when the automatic feed is in operation.

The wheel slide may thus be reciprocated at any one of several speeds, and the feed of the slide may be stopped and started at 50 will. The slide may also be moved manually by the hand wheel 84. The clutch collar 60 may be controlled by any common form of reversing mechanism, and is usually operated by means of dogs, not shown, 55 carried by the wheel slide 11.

A third shaft 90 is mounted in bearings 91 parallel to the shaft 31, and is provided with a set of change gears 92 loosely mounted thereon. A sliding key controlled 60 from a hand wheel 93 provides means for selectively securing one of the gears 92 to

the shaft 90, the mechanism being identical with that described in connection with the shaft 50. The bevel gear 23, previously described, is fixed to the outer end of the shaft 65 90, and through these connections the table 16 may be rotated at a selected speed.

The arrangement of gearing above described is exceedingly compact and enables me to secure all of the necessary feed 70 changes and manipulations by the use of exceedingly simple mechanism. By means of the handle 40 the entire feeding mechanism may be stopped and started, and by the use of the handle 80 the wheel feed may 75 be stopped and started independently of the table drive. After the wheel feed is stopped the wheel slide may be moved as desired by the hand wheel 84.

Having thus described my invention it 80 will be evident that changes and modifications may be made therein by those skilled in the art without departing from the spirit and scope of my invention as set forth in the claims, and I do not wish to be otherwise limited to the details herein disclosed, 85 but what I claim is:—

1. A grinding machine having, in combination, a wheel slide, a substantially horizontal work table, a drive shaft, a set of 90 gears fast on said shaft, a shaft for rotating the table and a wheel feed shaft each parallel to said drive shaft, a set of gears loose on each shaft and in mesh with the gears on the drive shaft, manually adjustable means to 95 secure a selected gear in each set to its respective shaft, and connections from said shafts to said table and slide.

2. In a grinding machine, a wheel slide, 100 a drive shaft, a wheel feed shaft parallel to said drive shaft, change gear connections between said shafts, a rack on said slide, a vertical shaft having a pinion engaging said rack, connections from said wheel feed shaft to said vertical shaft including a worm and 105 worm wheel and a friction clutch, and a hand lever connected to move said clutch.

3. A grinding machine having, in combination, a wheel slide, a substantially horizontal rotary work table, a drive shaft, 110 change gear connections from said shaft to said wheel slide and from said shaft to said rotary table, means to stop and start the wheel feed and the table drive simultaneously while the wheel is continuously driven, and additional means to stop the wheel feed while the table and wheel are continuously driven.

In testimony whereof I have hereunto affixed my signature.

ALDEN M. DRAKE.
